UNITED STATES PATENT OFFICE.

MURREL D. AIRGOOD, OF PUNXSUTAWNEY, PENNSYLVANIA.

MOISTENING DEVICE FOR INCUBATORS.

1,254,957.

Specification of Letters Patent.

Patented Jan. 29, 1918.

Application filed August 28, 1916. Serial No. 117,330.

To all whom it may concern:

Be it known that I, MURREL D. AIRGOOD, a citizen of the United States, residing at Punxsutawney, in the county of Jefferson and State of Pennsylvania, have invented new and useful Improvements in Moistening Devices for Incubators, of which the following is a specification.

This invention relates to incubators, and 10 it has particular reference to a device for supplying the requisite moisture to an incubator to produce the best results and for regulating or governing such supply. The invention has for its object to produce a 15 simple and improved attachment which may be readily applied to and used in connection with a conventional type of incubator for the purpose of supplying moisture to the air utilized for heating the interior of the 20 incubator.

A further object of the invention is to produce a moistening device which may be readily applied to the heating apparatus of the conventional incubator.

25 With these and other ends in view which will readily appear as the nature of the invention is better understood, the same consists in the improved construction and novel arrangement and combination of parts which 30 will be hereinafter fully described and particularly pointed out in the claims.

In the accompanying drawing has been illustrated a simple and preferred form of the invention, it being, however, understood 35 that no limitation is necessarily made to the precise structural details therein exhibited, but that changes, alterations and modifications within the scope of the claims may be resorted to when desired.

40 In the drawing,—

Figure 1 is a side elevation of an incubator equipped with the improved moistening appliance, a part of the heating apparatus being shown in section.

45 Fig. 2 is an enlarged sectional detail view of a portion of the heating apparatus and the moistening device.

Fig. 3 is a sectional detail view taken on the line 3—3 in Fig. 1.

50 Fig. 4 is a detail view partly in elevation and partly in section illustrating a modified form of the invention.

Fig. 5 is a sectional detail view taken on the line 5—5 in Fig. 1.

55 Corresponding parts in the several figures are denoted by like characters of reference.

The incubator casing A supports the heating apparatus which comprises a lamp or heater 15 and a flue casing C, the latter being composed of three substantially concentric cylinders namely an outer cylinder 16, an intermediate cylinder 17 and an inner cylinder 18. The inner cylinder, which constitutes the lamp chimney, is connected with the intermediate cylinder 17 by a tubular 60 passage 19 through which the products of combustion may pass from the lamp chimney to the space 20 between the outer and intermediate cylinders. Said space is closed at the lower end thereof by an annular 65 flange 21 and the outer cylinder is provided near its lower end with an exit 22 for the products of combustion. The inner cylinder 18 is closed at its upper end by a top member 23 and the outermost cylinder is 70 likewise closed by a top member 24. The intermediate cylinder, which terminates between the upper ends of the outer and inner cylinders is provided with an exit pipe 25 75 that extends through the top member 24 and is adapted to be obstructed by a valve or damper 26 which is operable in the customary manner by a thermostatic device in the incubator. The intermediate cylinder 17 is connected with the interior of the incubator by means of a pipe or duct 27 that 80 extends through the wall of the outermost cylinder.

The wall of the innermost cylinder 18 of the flue casing is apertured for the passage 90 of a supporting member 18' carrying at one end a metallic ball or body 19' which is located within the chimney flue directly above the flame of the heater. The supporting member 18' also carries a pan or receptacle 20' containing sand or other like refractory material which is adapted to absorb water, such material being indicated at 21'.

A tank 22' which is supported on the incubator casing is provided with an outlet pipe 23' equipped with a needle valve 24' and having an outlet nozzle 25' which terminates directly over the receptacle 20'.

In the operation of the device the tank 105 22' is filled with water which is permitted to pass through the pipe or duct 23' to the nozzle 25', the flow being regulated by the needle valve 24'. The supporting member 18', being composed of heat conductive material, connects with the trough or receptacle 20' which is filled with absorbent refractory

material, said material being heated by heat transmitted from the ball or body 19' through the member 18', thus vaporizing the water which is discharged to the refractory material, the vapor serving to moisten the air passing through the flue casing to the incubator. The air enters the space between the lower ends of the intermediate and inner cylinders 17, 18 in the space, the space between said cylinders being kept in a heated condition by the products of combustion passing upwardly through the cylinder 18 which constitutes the lamp chimney and through the space 20 between the intermediate and outer cylinders. The air being thus heated and supplied with moisture, passes to the incubator through the duct 27. Should the heat in the incubator rise above a predetermined degree, the valve 26 will be moved to the non-obstructing position shown in Fig. 1, and the heated moist air will then pass to the atmosphere until, by the lowering of the heat within the incubator, the valve is again moved to an obstructing position. The humidity in the incubator may be ascertained by the use of a hygrometer of ordinary construction, and by manipulating the needle valve the supply of water may be regulated according to the requirements.

In the modified form of the device shown in Fig. 4 the receptacle, here designated by 20" of absorbent refractory material is in the form of a tube extending through the top closure 23 of the chimney flue 18, the heating ball or body 19" being supported at the lower end of said tube directly in the path of the flame of the heater.

From the foregoing description, taken in connection with the drawing hereto annexed, it will be seen that I have produced a very simple and inexpensive device which is readily applicable to the heating apparatus of incubators of ordinary or conven-

tional construction and whereby the needed moisture to insure best results may be supplied without necessity for opening the incubator, such crude devices as sponges soaked in water or the like being entirely dispensed with, and means being provided whereby the supply of heated and moistened air may be very accurately determined and regulated.

Having thus described the invention, what is claimed as new, is:—

1. In a moistening device for incubators, the combination with a heater and a flue casing having an air inlet and an exit communicating with the interior of the incubator, of a receptacle supported within the flue casing and containing absorbent refractory material, and means for supplying water to said receptacle.

2. In a moistening device for incubators, the combination with a heater and a flue casing having an air inlet and an air exit communicating with the interior of the incubator and a smoke exit, of a receptacle supported within the flue casing and containing absorbent refractory material, and means for supplying water to said receptacle, said means including a supply tank, a duct having a terminal nozzle, and a regulating valve.

3. In a device of the class described, a heater, a flue casing, a supporting member of heat conductive material extending through a wall of the flue casing, a receptacle supported at one end of the supporting member containing absorbent refractory material, a heat conductive body carried at the other end of the supporting member and positioned in the path of the flame of the heater, and means for supplying water to the receptacle.

In testimony whereof I affix my signature.

MURREL D. AIRGOOD.
